DESIGN FOR A STAMPING TOOL OR THE LIKE

Jay Rosten, New York, N. Y.

Application June 8, 1937, Serial No. 69,737

Term of patent 7 years

To all whom it may concern:

Be it known, that I, Jay Rosten, a citizen of the United States of America and a resident of the county of Kings, city and State of New York, have invented a new, original, and ornamental Design for a Stamping Tool or the like, of which the following is a specification, reference being had to the accompanying drawing, forming a part thereof.

In the drawing:

Figure 1 is a side view in elevation of the stamp-

ing tool or the like, a portion of the electric cord being broken away for convenience of illustration.

Figure 2 is a front view in elevation of Figure 1.

Figure 3 is a bottom plan view of the stamping tool or the like.

I claim:

The ornamental design for a stamping tool or the like substantially as shown.

JAY ROSTEN.
